UNITED STATES PATENT OFFICE.

THOMAS W. BELL AND THOMAS C. ROGERS, OF PARKERSBURG, WEST VIRGINIA.

WIRE-LINE CLAMP.

Application filed March 24, 1927. Serial No. 178,097.

This present invention relates to a clamp for gripping well cables such as is used in the drilling of oil wells, and is an improvement on the clamp shown in our prior Patent No. 1,308,924.

The principal objects of the invention are the provision of a clamp of the type described which will have a guide thereon to facilitate bringing the drilling cable between the grips; which will have means for keeping the cable centered when the clamp is being tightened; which may be attached by one man; which will have means to prevent oscillation during drilling; and which will be capable of receiving a plurality of different sized cables at the same time. These and other objects and advantages will appear as the description proceeds.

In the drawings there is illustrated one form of the invention in which:

Figure 1 is a front view of a device embodying our invention.

Fig. 2 is a rear view thereof.

Fig. 3 is a perspective detail of a jaw assembly.

Fig. 4 is a side elevation.

Fig. 5 is a sectional plan view along the line 5—5 of Fig. 4.

Fig. 6 is a detail of the transverse link.

In the drawings, the clamp is shown to consist of a pair of jaws 1, having backwardly extending ears 2 adapted to receive a pin, so that the jaws are held together in a pivotal manner. The upper part of each jaw 1 terminates in a hook shaped part 3 adapted to receive the rings or links 4 carried by the temper screw (not shown) in the usual manner well known in this art.

Along one longitudinal edge of each clamp jaw is seated a grip slip 5 having a substantially concave face to receive the cable to be gripped. These slips are dovetailed in place longitudinally by the overhanging portions 6 of the jaws 1, and laterally at the back by the edge of part 17 and at the front by slip retainers comprising right angular members 7 having a horizontal portion adapted to rest on an arm 8 of jaw 1, and a vertical portion 9, grooved longitudinally to receive a second cable.

Each jaw 1 is provided with an arm 8 extending toward the front of the clamp. Beneath one of these arms is a handle 10 to aid the driller in closing the device. The other arm carries a clevis 11 having an elongated slot 12 therein, a pin 13 riding in this

slot securing the clevis to the arm. The unattached end of the clevis 11 is adapted to straddle the handle carrying arm when the device is closed. The attached end of the clevis 11 is threaded to receive a threaded bar 14, the end of which is drilled to take a handle member 15. This last named part may be welded around the drilled hole in the bar 14 so as to form a permanent T screw. The threaded end of the bar 14 abuts the end of the arm.

In order to get the desired leverage on the clamp jaws without putting a strain on the pivot pins carried by the ears 2, there is provided a transverse link 16 adapted to slip over rear extensions 17 of the jaws 1. Pins 18 hold the link 16 in position.

It will now be seen that by taking up on the T screw, the arms are made to approach each other in front, and the link 16 and extensions 17 receive most of the strain. As a result of this tightening up, the cable contained between either the grip slips 5 or the slip retainers 7 will be securely held thereby.

In placing the clamp it is very desirable that the driller be assisted in properly centering the cable in the grips, and this is done by providing a curved thumb 19 on the right hand jaw 1 slightly in front of the grip slip of that jaw. Such thumb guides the cable into proper engagement with the slip. Where desired a second thumb 19a may be located at the bottom of the jaw 1.

In operation on a drilling well, the clamp is hung on the temper screw (not shown) by the links 4, and as the clamps are heavier in front they pitch backward at the bottom hanging open before attaching the drilling cable. When attaching the clamp to the drilling cable, the driller stands in front of the clamp and reaching around the drilling line 20, grasps the clevis 16 with his right hand and the handle 10 with his left, and pulls the whole clamp forward until it surrounds the drilling line, then closes the arms of the clamp and holds them closed by swinging the clevis 11 over the end of the left arm. During this movement the thumb 19 has come in front of the cable 20 and guided it into the slips 5. By pulling forward and lifting on the handle 10, the grip slips are made to parallel the cable and the latter seats in the grooves therein. By tightening the T screw, the cable is secured.

This guiding the cable into the grip slips is an important part of this invention, as

frequently cable lines are cut when the clamp is tightened because the cable was not guided and centered in the slips.

It is common practice with drillers to loosen the clamps slightly and allow the cable to slip in order to drill a further depth. This sometimes results in cutting the cable if it is not perfectly centered in the grooves of the grip slips. The thumb 19 prevents this loss.

During drilling operations with reciprocating cable tools, the weight of the tools is alternately thrown on and taken off the cable. This results in a corresponding stretching or pulling of the twist or lay out of the line, and when the weight is taken off, the twist restores itself.

As a result of this action over the entire length of cable, there is set up an oscillating motion in the clamp which is very dangerous to the driller. To overcome this motion, a rod or other convenient means, termed a "jockey stick" is fastened at one end to the clamp so that that end can reciprocate with the tools, the other end being hinged usually to a stationary upright post termed a "headache post." Frequently the jockey stick comes loose from the clamp, no provision being made to adequately secure this stick to the clamp. This inefficiency has been overcome by providing at the rear of the link 16, two spaced apart perforated ears 21 adapted to receive one end of the jockey stick 22 which may be made fast by a pin 23. The other end may be hinged to the headache post in the usual manner as is well known.

Another important advantage occurring as a result of this novel construction, lies in the fact that the slip retainers 7 are grooved to receive a second cable. It is frequently necessary when drilling tools become stuck, to run other tools on another line, generally on what is known as a sand line, to loosen and recover the drilling tools. This has usually been done by tying the sand line to the clamp in some way; with unsatisfactory results. With the present construction, the grooved slip retainers may be advantageously used to grip the sand line 24 without removing the drilling cable from the clamp.

It will be noted that the links 4 are provided with a central rib and that the pair of eyes thus formed have their side walls at such an angular inclination that by no possibility can these links kink or become otherwise permanently twisted as the strain on

the drilling cable is alternately released or increased. This angular inclination together with the central strengthening rib 60 constitutes an important feature of the invention and are more to be desired than the ordinary form of link.

What we claim is:

1. A cable clamp comprising cooperating jaws, each jaw having a cable receiving groove therein, means to force a cable into said groove between the jaws, and means to secure the jaws on the cable, said means comprising a curved thumb carried by one jaw 70 and extending in front of the cable receiving groove.

2. A cable clamp comprising cooperating jaws, a cable grip slip held in each jaw, a grooved slip retainer, in proximity to each 75 slip and holding the same in place, and means to close the jaws simultaneously upon cables located between slips and slip retainers.

3. A cable clamp comprising cooperating jaws, a cable grip carried by each jaw, a forwardly extending arm on each jaw, a handle on one arm, and a sliding clevis on the other arm adapted to straddle the first mentioned arm, and a tightening device for bringing the two arms together to grip a cable held between the jaws.

4. A cable clamp comprising cooperating jaws, said jaws having rear extensions, a transverse link straddling said extensions, 90 arms on the front of said jaws, means to secure said arms together and means carried by said transverse link to receive a jockey stick to prevent undue oscillation.

5. A cable clamp comprising cooperating 95 jaws, said jaws having rear extensions, a transverse link straddling said extensions, arms on the front of said jaws, means to secure said arms together and means carried by said transverse link to receive a jockey 100 stick to prevent undue oscillation, comprising spaced apart perforated ears.

6. A cable clamp comprising cooperating jaws, each jaw having a cable receiving grip slip therein, each slip terminating short of the top of the jaw, that portion of the meeting faces of each jaw being within the plane of the meeting faces of its slip, and a curved thumb on one jaw above its slip projecting in front of the cable receiving groove.

In testimony whereof, we affix our signatures.

THOMAS W. BELL.
